US0D1076873S

(12) **United States Design Patent** (10) Patent No.: **US D1,076,873 S**
(45) Date of Patent: ** May 27, 2025

(54) **BONE CONDUCTION HEADPHONE**

(71) Applicant: **Suzhou Mojawa Intelligent Electronics Co., Ltd.**, Suzhou (CN)

(72) Inventors: **Feng Deng**, Jiangsu (CN); **Haijuan Li**, Jiangsu (CN); **Hongbin Cao**, Jiangsu (CN)

(**) Term: **15 Years**

(21) Appl. No.: **35/520,979**

(22) Filed: **Apr. 1, 2024**

(80) **Hague Agreement Data**

Int. Filing Date: **Apr. 1, 2024**

Int. Reg. No.: **DM/236990**

Int. Reg. Date: **Apr. 1, 2024**

Int. Reg. Pub. Date: **May 24, 2024**

(30) **Foreign Application Priority Data**

Jan. 5, 2024 (CN) 202430007862.1

(51) **LOC (15) Cl.** **14-01**

(52) **U.S. Cl.**

USPC **D14/205**

(57)

CLAIM

The ornamental design for bone conduction headphone as shown and described.

DESCRIPTION

1.1: Front perspective view

1.2: Front perspective view

1.3: Front elevational view

1.4: Back elevational view

1.5: Top plan view

1.6: Bottom plan view

1.7: Left elevational view

1.8: Right elevational view

1.9: Perspective view; the enlarged encircled portion A

1.10: Enlarged view of reproduction **1.9**, portion A; the circles in portion B are transparent

1 Claim, 10 Drawing Sheets
